UNITED STATES PATENT OFFICE.

ADOLPH FABER DU FAUR, OF NEWARK, N. J., ASSIGNOR TO EDWARD COOPER AND ABRAM S. HEWITT, OF NEW YORK, N. Y.

GAS-PRODUCER.

SPECIFICATION forming part of Letters Patent No. 225,813, dated March 23, 1880.

Application filed October 17, 1879.

To all whom it may concern:

Be it known that I, ADOLPH FABER DU FAUR, of Newark, in the county of Essex and State of New Jersey, have invented a new and useful Improvement in Gas-Producers, which improvement is fully set forth in the following specification, reference being had to the accompanying drawings, in which—

Figure 1 is a vertical section in the plane of the line $y y$, Fig. 2. Fig. 2 is a horizontal section in the plane of the line $x x$, Fig. 1, of a gas-producer embodying my invention. Fig. 3 is a vertical section of my producer, showing different modifications. Fig. 4 is a vertical section of a square producer constructed of fire-brick, embodying my invention, in combination with the grate of the producer known as the "Tessié Gas-Producer," or substitute for a grate.

Similar letters indicate corresponding parts.

My invention relates to gas-producers wherein solid fuel is converted into carbonic oxide.

In all gas-producers heretofore known, whether having a horizontal or an inclined grate, or no grate at all, the hot gases in their ascent would pass toward the side walls and cause clinkers to adhere to the walls, sometimes forming arches, preventing the descent of the fuel and interrupting the operation of the producer. This happens particularly when the producer is run fast—that is to say, when it consumes a large quantity of fuel.

The object of my invention is to prevent the adhesion of clinkers to the side walls, and this I accomplish by feeding the fuel from all sides toward a central fire, and by drawing off the gases at the center.

The producer represented in Figs. 1 and 2 is constructed essentially of cast-iron, although brick-work may be used.

a is an annular hopper, which, together with the bell b , forms the fuel-charging apparatus. When the bell b is raised, which can be done by means of a forked lever and connecting-links or other suitable devices, the fuel drops into the annular space c surrounding the bell-shaped gas-hood d , which is supported by brackets secured to the outer shell, s , or otherwise suspended. The fuel is thus fed from all sides

to the conical dead-plate f , and to the conical grate or fire-pot g , which, as shown in the drawings, consists of perforated castings, leaving a large opening in the center, through which ashes and clinkers pass into the ash-pit.

The space outside of the grate or fire-pot is inclosed by iron walls, with doors k for the removal of ashes and clinkers. $i i$ are blast-pipes for leading the blast into this space. When the producer is to be operated with natural draft the ash-pit is left open. $h h h$ are holes for stirring or poking the fire. They are provided with doors or dampers of the usual construction.

In this producer the fuel-feed is a peripheral feed—that is to say, the fuel passes from the periphery or from all sides along the outer walls toward the center, while the hot gases travel upward toward the central gas-flue d .

My producer, with its inclined conical dead-plate and its inclined conical grate, differs essentially from the Siemens producer in having no side walls, such as the side walls of the Siemens producer, which in the Siemens producer are separate and distinct from the dead-plate and inclined grate, and are necessary to complete the fuel-chamber, and which, being in direct contact with the hot fuel and gases, cause clinkers to adhere and form arches. Every vertical cross-section of my producer passes through the inclined dead-plate and grate, and all the horizontal sections through the dead-plate, as well as through the grate, are practically closed figures, being in the present example circles.

My producer may be round or square or of any other shape, and may be constructed of any material used in the construction of furnaces.

The central gas-hood, instead of being constructed of cast-iron, may be of fire-brick, particularly when a square fire-place is used, as shown in Fig. 4, where d is the gas-hood formed by arches, from the outer edges of which the fuel slopes toward the center.

Various charging arrangements may be used instead of the bell. The space c may also be branched into two or more funnels contracted

at the top, each with a separate charging apparatus—as, for instance, the hopper *a* and slide *b* in Fig. 4. With some fuels the upper part above *c* may be left open.

5 The central gas-hood, *d*, may also be a dome or dome-like casting, with one or more flues, *m*, carrying the gas out through the sides to a receiver, *n*, as shown in Fig. 3, where the fuel is charged through an apparatus, *a b*, located 10 centrally above the gas-dome.

The grate may be formed of grate-bars of any construction, such as step-grates or partly step-grates and partly perforated plates, as indicated in Fig. 3, or the grate of the producer 15 known as the "Tessié Gas-Producer" may be used, as shown in Fig. 4, applied to a square producer where the dead-plate *f* is built of brick-work.

Where the locality admits of it, the funnel-shaped bottom of the ash-pit may have a vertical tube, *o*, Fig. 3, projecting downward into the water-vessel *p*, the lower end being beneath the surface of the water. The tube *o* is 20 kept full of ashes and clinkers, part of which are from time to time removed through the water-pan, the water preventing the blast from 25 passing out through the tube, as shown in Fig. 3.

The lower part of the producer—that is to say, the ash-pit and the blast-chamber—may also 30 be sufficiently enlarged to admit a man and give him room enough to do all the work necessary at the fire-pot and ash-pit, the enlarged space having double doors for ingress and egress. By this arrangement the fire can be attended 35 to without the necessity of shutting off the blast.

Prior to my invention central gas-conduits

have been used in blast-furnaces; but in such they do not in the lower part of the furnace, at or near the zone of incandescence, drive the 40 current of hot gases away from the walls toward the center, so as to prevent the adhesion of clinkers to the walls, which results are secured by my construction and arrangement.

Central gas-conduits have also been used in 45 apparatus for manufacturing illuminating-gas; but in such the conduits were not open at the bottom, and consequently could not drive the current of hot gas toward the center.

What I claim as new, and desire to secure 50 by Letters Patent, is—

1. The combination, in a gas-producer, of a central gas-hood, open at the bottom and extending close to the zone of incandescence, an inclined dead-plate, the horizontal sections of 55 which are closed figures, an inclined fire-pot grate, the horizontal sections of which are closed figures, and a central discharge for ashes and clinkers, substantially as and for the purpose specified. 60

2. In a gas-producer, the combination, with the dead-plate, of an inclined funnel-shaped fire-grate, which is arranged below and in continuation with said dead-plate, substantially as described, whereby said grate in the zone 65 of incandescence takes the place of side walls, as set forth.

In testimony that I claim the foregoing I have hereunto set my hand and seal this 16th day of October, 1879.

A. FABER DU FAUR. [L. S.]
